PREVENTING FOULING OF METAL CONDUCTORS IN A REFINERY PROCESS

Richard M. Miller, La Grange, and Harold I. Patzelt, Chicago, Ill., assignors to Nalco Chemical Company, a corporation of Delaware
No Drawing. Filed Jan. 19, 1959, Ser. No. 787,353
7 Claims. (Cl. 208—48)

This invention relates to improvements in the intermediate refining stages of petroleum hydrocarbons. Specifically, the invention is concerned with chemical additives for normally liquid charge stocks used to produce liquid and gaseous hydrocarbon fuels.

It is common practice to add chemical agents to finished petroleum hydrocarbon products such as gasolines, kerosenes, fuel oils, finished solvents, and the like, to give these products desirable properties and characteristics. Modern refining operations use a large number of charge stocks which are intermediates in the production of finished petroleum products. Until recently little attention was paid to the properties of these charge stocks since they were rapidly processed through the refining equipment where they were converted to products having different physical and chemical characteristics than those of the starting material.

With the ever-increasing need for higher octane gasolines, improved aviation fuels and improved residual fuels, it has become the practice to treat the various refinery charge stocks to extract improved fuel values therefrom. These various processes, while greatly improving the fuel yield of a given charge stock, have tended to increase refining problems which, in the past, were not critical.

One of the worst problems encountered in the treatment of various petroleum charge stocks is the phenomenon which is now recognized and is descriptively called fouling. This phenomenon manifests itself in the form of deposits which frequently form on the metal surfaces of the processing equipment and tend to materially decrease the efficiency of the intermediate refining operations. The direct results of fouling appear in the forms of heat transfer loss, increased pressure drops, loss in through-put and, in some instances, a specific type of corrosion product which is associated with the deposits.

The charge stocks which most commonly cause fouling in the intermediate refinery equipment are naphthas, gas oils, and crudes. The naphthas or light distillate stocks may be considered as a light oil, at least 10% of which boils below 347° F. and at least 95% distills below 464° F. The gas oils which frequently are referred to as middle distillates usually are intermediates between the so-called kerosene fractions and the light lubricating cuts. These gas oils are usually used as charges to cracking units where the molecules are broken down into smaller components. The crude oils which most commonly cause the problem of fouling are virgin products charged to the first refining stage operations and contain all of the petroleum fractions normally removed in the refining processes. For the purposes of this invention, crude stocks are intended to cover the so-called residual or pot fractions which remain after the volatile components and solvent extractable components of the crudes have been removed.

The various charge stocks mentioned above are most frequently subjected to one or more of the following general type processes to produce fuels: reforming, cracking,

2

alkylation, isomerization, polymerization, desulfurization, hydrogeneration, and dehydrogenation. These processes may be performed using a number of specific refining techniques which frequently employ catalytic reagents. A description of these various processes and their modifications are described in the publication, Petroleum Refiner, September 1958.

The deposits previously mentioned most frequently occur at elevated temperatures which range between 200° F. and 1100° F. The types of mechanical equipment most commonly affected are furnaces, heat exchangers, reboilers, and condensers. In these types of equipment, the charge stock is usually caused to flow through various types of heat processing equipment such as pipes, heat exchangers, furnaces, etc. which, for purposes of simplification, are referred to herein as conductors.

The deposits forming on the metal surfaces thus described are varied in composition and may be either organic, inorganic, or mixed organic and inorganic, with the latter type deposit being the most common type found in intermediate refining processes. The organic deposits are primarily polymerization products and are usually black, gummy masses which may be converted to coke-like masses at elevated temperatures. The inorganic portions of the deposits will frequently contain such components as silica, iron oxide, sulfur trioxide, iron sulfide, calcium oxide, magnesium oxide, inorganic chloride salts, sodium oxide, alumina, sodium sulfate, copper oxides, and copper salts. The source of the inorganic components of the deposits is difficult to locate in any one given refining operation, but frequently they may be ascribed as coming from such sources as ash components of the crude oils, corrosion products from the metal surfaces the charge stocks contact, and contaminants resulting from the contact with the various metallic catalytic reagents used to process the stock.

The problems described above are distinguishable from the prior art phenomena of corrosion and sludge formation which frequently occur in finished products. The problem of sludge or deposit formation in finished products is not related to that of organic fouling since deposits of the former type may be readily solubilized using such organic solvents as benzene, acetone, and the like. The deposits which are referred to herein as fouling are not readily solubilized by common organic solvents. The inorganic deposits which occur as fouling products are frequently much more complex in their make-up than the conventional corrosion products; hence they are readily distinguishable on this basis.

When the fouling phenomenon first became apparent, it was believed it could be corrected by using known anti-oxidants or stabilizing chemicals to mitigate the problem. The experience with these additives soon developed the fact that conventional petroleum additives were relatively ineffective.

It would be a valuable contribution to the art if the problems described above could be overcome by using economical chemical additives at relatively low dosages. This invention presents such a solution to the problem.

The invention in its simplest form comprises a petroleum refining process for the production of liquid and gaseous hydrocarbon fuels wherein a normally liquid charge stock flows through a metal conductor under conditions of temperature and pressure which cause the formation of deposits on the surfaces of the metal conductor. To prevent the formation of these deposits or

fouling, the process is performed in the presence of a chemical additive which is admixed with the charge stock. The chemicals capable of preventing the fouling are oil soluble, alkaryl sulfur-containing compounds, which contain a sulfonic acid radical. Compounds falling under this general category are the well-known petroleum sulfonic acids and alkyl benzene sulfonic acids and their salts of the general formula:

In the above formula R is an alkyl radical from 8 to 22 carbon atoms in chain length and x is an integer from 1 to 3. The constituent M will be explained more fully hereinafter.

The oil soluble petroleum sulfonic acid may be said to be those sulfonic acids having a molecular weight of at least 350-375. In a preferred embodiment of the invention the molecular weight of the sulfonated treating agent is in excess of 415, and may even exceed 1,000. Included in the grouping of petroleum sulfonates are the well-known alkyl substituted sulfonated naphthalenes.

As will be shown later, when the sulfonic acid grouping in the molecule has been converted to the alkali metal salt form the sodium or potassium salts of a given acid will in most cases give results superior to those obtained when the free acid is used.

Due to the inherent corrosiveness of the free sulfonic acids, it is usually desirable from a handling standpoint to employ the reagents in the form of their salts, which salts may be derived from a rather large number of anionic components. Thus, for instance, the amine salts may be used, as well as the alkaline earth metal salts.

In some instances, particularly where the charge stock is a gas oil which is to be catalytically converted using a silica-alumina type catalyst such as, for instance, a fluidized catalyst used in a moving bed process, alkali metals tend to contaminate the catalyst; hence are not too well suited for this type of operation. When such conditions are present, it is then expedient to use either the ammonia or amine salts of the sulfonic acids which give satisfactory performance and do not have the disadvantages of catalyst contamination. In referring back to the formulas of the alkyl benzene sulfonic acid, the constituent M may then be considered as being either hydrogen, alkali, alkaline earth, or an organic amine grouping. For purposes of illustrating several oil-soluble alkaryl sulfur containing compounds, the Table I is presented. Table IA lists several commercial stabilizers and anti-oxidants which will be compared to the compositions of the invention in the examples.

TABLE I

Composition Number	Alkaryl S Compound	Molecular Weight
I	Petroleum sulfonic acid.....	405
II	do.....	400
III	Sodium petroleum sulfonic acid.....	415-430

Composition Number	Identification
XIV.....	2,4,6-tertiary butyl phenol.
XV.....	Copolymer of lauryl methacrylate and diethyl ethanol amine methacrylate.

The compositions are used at dosage ranges from as little as one part per million to dosages ranging as high as 300 to 500 parts per million. The optimum treatment level which will work is dependent upon the type of charge stock, the type of intermediate refining operation to which the stock is subjected, and the temperature at which the particular process is performed. As a general rule, the dosage range for crudes will be between 5 parts per million and 300 parts per million. In the case of naphthas, the dosage range will be between 10 parts per million and 200 parts per million, with a preferred treating range being at between 5 and 100 parts per million. When gas oils are treated, the dosage may vary from 5 parts per million to 300 parts per million, with optimum dosage levels being between 5 and 100 parts per million.

One of the most interesting features of the invention is that the additive remains preferentially with the liquid phase of the charge stock during the various refining stages. Thus, for instance, if a gas oil is subjected to a catalytic process, the additive does not carry over to any appreciable extent into the finished product, but will remain behind with the residual and non-converted components of the liquid or deposit itself on the surface of the reactor. In the case of residual fuels, the additive will be carried over into the finished fuel product, but this is the only case wherein the additive will be found to any appreciable extent in a finished hydrocarbon product.

The additives may be added to the charge stock at any point in the process to be protected and will carry along with the production until such a point in the refining operation where the product is converted into a different chemical component or species.

Thus, where a crude stock is passed through heat exchangers to a thermal distillation unit to remove the lighter fractions, the additive may be added just prior to the heat exchanger section of the operation and will afford protection to both the exchanger surface and other surfaces of the distillation or fractionation unit.

By indicating that the surfaces of the various units are protected, it is meant that the charge stock has been rendered non-fouling as to the metal surfaces; hence, deposit build-up does not occur. The process may, therefore, be considered as preventative rather than corrective in its operation. In some cases, the additives will remove existing fouling, but in most instances, the function of the additives is to prevent fouling rather than remove existing deposits.

As indicated earlier, the components of the deposits will vary in their chemical constituents and frequently contain a large number of ingredients. For purposes of greater understanding, Table II below is presented to illustrate the types of deposits which the additives of the invention tend to prevent.

ess consists of a variable injection pump, a recycle loop in which an electrically heated heat exchanger tube is incorporated, and a variable recycle pump in the loop.

The heat exchanger tube consists of an insulated resistance wire coil wound around a thick wall tube. The fluid being tested flows through the tube. The oil temperature at the outlet of the exchanger tube and the wall temperature of the tube are recorded continuously.

The fouling of the tube is determined by the change in heat transfer coefficient during the test after equilibrium has been attained. This coefficient is determined from the following equation:

$$Q = UA\Delta t$$

where:

Q = heat input to the oil, B.t.u./hr.

U = heat transfer coefficient, B.t.u./hr.

A = area of heat transfer surface based on the internal surface area of the exchanger tube, ft.².

Δt = difference between the oil and wall temperatures, ° F.

The following is a description of the various charge stocks used:

A. Gas oils

B. Crude oils

C. Blended heavy and coker naphtha

D. Blended virgin naphtha and thermal cracked naphtha

E. Platinum reformer naphtha

The results of the tests are reported in Table III. To more completely understand the results, the following general comparisons are presented to clarify the percent reduction in fouling tabulations:

	Percent
Poor	<20
Fair	20-50
Good	50-70
Excellent	70-100

Although not reported in Table III, comment should be made on the nature of the deposits found on the surfaces of the specimens. Without treatment the typical deposit is in the form of layers with the inner part contacting the tube surface being dense and coke-like. The outer deposit coats tend to be sticky, semi-fluid-like masses.

Using the treatment of the invention, the deposits when present are usually light fluids which are readily removed using conventional cleaning techniques. In all cases the deposits are materially lessened over the blanks.

The invention is claimed as follows:

- 50 1. Process for preventing fouling of a metal conductor through which is passing material from the group consisting of naphthas, gas oils and crude oils which are normally susceptible to the formation of fouling deposits when passed through such metal conductor at 200-1100° F. for conversion of said material to an upgraded refinery product, which comprises adding to said material at least one part per million, based on the weight of said material, of an oil soluble alkaryl sulfur containing compound having a molecular weight of 350 to 1055 from the group consisting of petroleum sulfonic acids, their alkali, alkaline earth metal, and amine salts and alkyl benzene sulfonic acids and sulfonates of the formula

where R is an alkyl radical of from 8 to 22 carbon atoms in chain length, x is an integer from 1 to 3, and M is from the group consisting of hydrogen, alkali, alkaline earth metal, and amine, the amount of said oil soluble alkaryl

sulfur-containing compound being sufficient to reduce the formation of said deposits on the surface of said metal conductor in contact with said material.

2. The process of claim 1 where the charge stock is a petroleum hydrocarbon liquid from the group consisting of crude oils, gas oils, and naphthas.

3. The process of claim 1 where the alkaryl sulfur compound is an alkali metal salt of an oil-soluble petroleum sulfonic acid.

4. The process of claim 1 where the alkaryl sulfur-containing compound is an alkali metal dodecyl benzene sulfonic acid containing from 1 to 3 dodecyl radicals.

5. Process for preventing fouling of a metal conductor through which is passing material from the group consisting of naphthas, gas oils and crude oils which are normally susceptible to the formation of fouling deposits when passed through such metal conductor at 200-1100° F. for conversion of said material to an upgraded refinery product, which comprises adding to said material at least one part per million, based on the weight of said material, of an oil soluble alkaryl sulfur containing compound having a molecular weight of 350 to 1055 and the following chemical structure

where R is an alkyl radical of from 8 to 22 carbon atoms in chain length, x is an integer from 1 to 3, and M is from

the group consisting of hydrogen, alkali, alkaline earth metal, and amine, the amount of said oil soluble alkaryl sulfur-containing compound being sufficient to reduce the formation of said deposits on the surface of said metal conductor in contact with said material.

5 6. The process of claim 5 where the alkaryl sulfur compound is the ethylene diamine salt of an oil-soluble petroleum sulfonic acid.

10 7. The process of claim 5 where the alkaryl sulfur-containing compound is the ethylene diamine salt of a dodecyl benzene sulfonic acid which contains from 1 to 3 dodecyl groups per molecule.
